(57) **CLAIM**

The ornamental design for a phone connector assembly, as shown.

DESCRIPTION

FIG. 1 is a top left perspective view of the present phone connector assembly;

FIG. 2 is a left side view of the phone connector assembly illustrated in FIG. 1;

FIG. 3 is a right side view of the phone connector assembly illustrated in FIGS. 1 and 2;

FIG. 4 is a rear view of the phone connector assembly illustrated in FIGS. 1 to 3;

FIG. 5 is a top view of the phone connector assembly illustrated in FIGS. 1 to 4; and,

FIG. 6 is a bottom view of the phone connector assembly illustrated in FIGS. 1 to 5.
